UNITED STATES PATENT OFFICE.

LESTER P. BARLOW, OF DETROIT, MICHIGAN.

ENGINE-COOLING SYSTEM.

Application filed December 30, 1926. Serial No. 157,900.

This invention relates to improvements in steam or vapor cooling systems for internal combustion engines of the suction and compression type, as usually employed for 5 automotive and other purposes.

In accordance with my invention, I utilize a portion of the suction produced by the engine during the operation thereof to automatically supply liquids to the cylinder 10 jackets of the engine to compensate for the liquids going off as steam in said jackets, and thus avoid the use of any force pumps, gears, shafts, etc. for forcing the liquids to the water jackets, as in steam or vapor cooling systems heretofore designed. By doing 15 away with pumps and substituting the vacuum lift principle for supplying liquids to the jackets, the amounts supplied to the jackets will be in direct proportion to the amounts going off as steam in the jackets 20 without regard to the speed of the engine. In doing this I overcome one of the great difficulties of steam cooling, namely, in not oversupplying the jackets with liquids at 25 high speeds of the engine, or when the engine is idling and not under load as in automobiles when coasting down long grades. With the elimination of force pumps and 30 their necessary driving gears and shafts, and employing the vacuum lift principle of my invention, the silent operation of the engine will be greatly improved, and moreover the cost of the assembly and its installation will be greatly reduced.

35 A further object of my invention is to provide a quick snap acting valve for intermittently opening and closing the suction and vent ports, respectively, of the vacuum lift tank, thereby quickly opening and closing 40 such ports at the instant necessary and not destroying the efficiency of the engine carbureting conditions or supplying more than the desired amount of air to the motor.

Other and further objects of my invention 45 will appear from the following specification, taken in connection with the accompanying drawings, in which—

Fig. 1 is a diagrammatic view of an internal combustion engine having a vapor 50 or steam cooling system embodying the vacuum lift principle of my invention;

Fig. 2 is an enlarged vertical sectional view through the vacuum lift tank to show 55 the quick acting, float actuated valve mechanism therein; and

Fig. 3 is an enlarged sectional view of a fitting which may be connected with the vent port of the vacuum lift tank.

In Fig. 1, 1 indicates an internal combustion engine of the suction and compression type, as employed on motor vehicles, and having a water jacket 2 about the cylinders thereof. A steam dome 3 is connected with the jacket 2 and extends above the normal level *a* of the liquids therein. 60

Associated with the engine is a condenser 4, which may be in the form of the usual automobile radiator with its upper and lower tanks 5, 6 and its interposed core structure as in radiator design. A conduit 7 connects the steam dome 3 with the upper tank 5 of the condenser so as to convey steam from the dome to the condenser, in which the steam is condensed as it passes down through the condenser to be returned as liquid to the jacket 2 through the supply and reserve reservoir 8. 75

The reservoir 8 is located below the water jacket 2 and is connected by a conduit 9 with the lower tank 6 of the condenser, so as to convey the condensate from the condenser into the reservoir. This lower tank 6 is provided with a vent 10 open to the atmosphere so that any air in the condenser 4 may escape as the steam enters the same. 80 The reservoir 8 is provided with a filler neck 11, normally closed by a cap in which is a vent 12, also open to the atmosphere. 85

A second tank 13 is located above the reservoir 8 and is so positioned with respect to the dome 3 that the tank 13 extends above and below the water level *a* in the dome. A conduit 14 connects the bottom of the reservoir 8 with the portion of the tank 13 above the liquid level *a* therein, while a conduit 15 connects the bottom of the tank 13 with the liquid intake 16 of the jacket 2, such intake being preferably at the lower portion of the jacket, as shown in Fig. 1. 90 A check valve 17 is located in the conduit 15 to prevent suction in the tank 13 from withdrawing water from the jacket 2 during the operation of the system. 95

As shown in Fig. 2, the top wall of the tank 13 is provided with a valve housing 18 having oppositely disposed ports 19, 20, the former being connected by conduit 21 with the suction side of the motor or engine 1 in the particular assembly shown in Fig. 1. This is accomplished by connecting 100 105 110

the conduit 21 with the fuel intake manifold or conduit 22 of the engine so that there will always be a suction on this conduit regardless of the position of the throttle valve (not shown) of the carburetor 23.

The housing 18 is provided with a chamber 24 connecting the ports 19, 20 with the interior of the tank 13. An endwise movable plug valve 25 is located in this chamber 10 so as to intermittently open and close the ports 19, 20. Depending from the housing 18 is a bracket 26 to the lower end of which is pivoted a trigger lever 27 having a slight lost motion connection (pin and slot) at its 15 upper end with the valve 25 intermediate its ends, as shown in said Fig. 2.

Located in the tank 13 is a plunger 28 arranged substantially at right-angles to the trigger 27 and having one end bearing 20 against the trigger adjacent its fulcrum. The opposite end of the plunger 28 has a sliding fit in a socketed member 29, which is pivoted at 30 to the upright wall of the tank 13. A coil spring 31 surrounds the 25 plunger 28 between a flange thereon and the outer end of the socketed member 29 to constantly urge or force the plunger against the trigger 27. A float 32 is located in the tank and is suspended from the plunger 28 forward of the spring 31 by a rod 33, which has a slight lost motion connection (pin and slot) with the plunger 28, as shown.

Port 20 is open to vent the tank 13 in the rising and falling of the float 32. The valve 35 25 is moved back and forth to intermittently open and close the ports 19, 20. When the port 19 is open, suction is created in the tank by the engine and serves to lift water into said tank from the reservoir 8. The 40 latter has a size or capacity sufficient to hold a relatively large body of water so as to aid in reducing the heat of the condensate entering the reservoir from the condenser and thus permit liquids to be drawn from the 45 reservoir to the tank 13 at a higher level by suction. The large body of water held by the reservoir 8 also allows for the make up of the loss of liquid from the system by natural evaporation.

The water entering the tank 13 raises the 50 float 32 and, when the maximum level is reached in the tank, the valve 25 is moved quickly to close the suction port 19 and open the vent 20, thereby allowing the water in 55 the tank to flow by gravity into the engine jacket 2. When first placing the system in operation, the action described repeats as fast as the tank 13 can fill and empty until the jackets 2 are filled to approximately the 60 level α in Fig. 1. Thereafter, when the level in the jackets 2 is lowered as by steam being generated in the jacket, the corresponding 65 level in the tank 13 also lowers to the same extent, thereby allowing the float 32 to recede and effect the throwing of the valve 25

to place suction on the tank 13 and thereby lift the required amount of liquid from the reservoir 8 to make up for the loss by steam in the jacket 2. When this happens, the tank 13 is again vented and the liquids so 70 lifted allowed to flow to the jacket 2 to replenish the liquids going off in steam. This action repeats itself during the steaming of the system, and serves to maintain a substantially constant level in the jackets so that 75 no opportunity is afforded for boiling away of the water to overheat the engine. After the jackets 2 have been once filled with liquids in the manner described, and the engine stopped, water remains in the jackets 80 2 to substantially the level as shown, so that on starting the motor, the float action does not come into play until after the vaporizing point of the cooling liquid has been reached. and the level α lowered, as above described. 85

When the tank 13 is filled, the level of the water is approximately at β , and the float 32 then holds the plunger 28 above the fulcrum of the trigger 27. The spring 31 is thus allowed to exert its outward pressure on the 90 trigger to hold the valve 25 in position closing the suction port 19, as shown in Fig. 2. The suction of the motor will also aid in holding the valve in this position. As the tank 13 empties into the jackets 2, the float 95 32 does not immediately drop with the receding liquid level but is held up by the tension of the spring 31. When the liquid in the tank recedes to the approximate level indicated by ϵ , then the weight of the float 100 32 is sufficient to overcome the tension of the spring 31, thereby drawing the plunger 28 down past the fulcrum of the trigger. In this movement, the spring 31 is slightly compressed as the plunger 28 passes the center 105 of the fulcrum and expands when below the fulcrum so as to effect the quick snap movement required to close the vent 20 by the valve 25 and open the vacuum port 19 for a 110 refilling of the tank.

To limit the raising and lowering of the float 32, suitable stops 34, 35 may be employed either directly on the float or on the tank or between the trigger 27 and its plunger 28, as shown in Fig. 2. The stops 34, 35, 115 120 when on the trigger 27 as shown in Fig. 2, are immediately above and below the respective maximum limits of the up and down movements of the plunger 28.

In Fig. 2, I have shown the port 20 in 120 direct communication with the atmosphere, there being a suitable air screen fitting 36 for the same. When this vacuum lift system is employed in combination with heavy 125 duty motor tractors or trucks, where the motor is operating at its maximum and imparting a great volume of heat to its cooling liquid, a back pressure may develop at the condenser. This back pressure will tend to depress the water level α , and such depres- 130

sion effect would resist the flow of the liquids from tank 13 to the jackets 2. To overcome this back pressure or neutralize its effect, I connect the vent passage 20 of the tank 13 to the conduit 7 allowing steam to flow in this passage instead of free air. This neutralizes the pressure in tank 13 and the jacket 2. To accomplish this, I may provide a valve fitting as shown in Fig. 3. This fitting is attached to the vent port 20 and contains an endwise movable plug valve 37 having a surrounding groove 38 between its ends and designed to be brought into register with either the air vent passage 39 or the passage 40 which leads into the steam conduit 7. When the groove 38 is in register with the passage 39, the system will be vented to the atmosphere, the same as shown in Figs. 1 and 2. On the other hand, when the groove 38 is in register with the passage 40, then steam may at the proper time enter the vacuum tank 13 to have the neutralizing effect described.

By the system and structure described, the advantages heretofore set forth may be accomplished, and I do not wish to be restricted either to the details of structure or to the arrangement of parts shown and described, as these may be variously changed and modified without departing from the spirit and scope of my invention.

The active part of the system is of course at the jackets 2, where the cooling of the engine takes place by the presence of the cooling liquids in contact with the hot cylinder walls. The inactive part of the system is elsewhere, as in the reservoir 8. Thus with my invention, a portion of the suction created by the engine in the fuel intake is utilized to transfer liquids from the inactive to the active portion of the system. Moreover, this transfer takes place from the inactive portion which is located entirely below the jackets or the active portion.

I claim as my invention:

1. The method of supplying cooling liquids to a vapor cooling system of an internal combustion engine of the suction and compression type, which consists in utilizing a portion of the suction produced by the engine in its fuel intake conduit for transferring cooling liquids from an inactive part of the system to an active part thereof adjacent the water jackets of the engine, and for automatically maintaining the liquids at a substantially predetermined level in the jackets.

2. The method of supplying cooling liquids to a vapor cooling system of an internal combustion engine of the suction and compression type, which consists in utilizing a portion of the suction produced by the engine in its fuel intake conduit for supplying cooling liquids to the active portion of the system from an inactive portion located

entirely below the level of the active portion, and for automatically maintaining the latter at a substantially predetermined level.

3. The method of supplying cooling liquids to a vapor cooling system of an internal combustion engine of the suction and compression type, which consists in utilizing a portion of the suction produced by the engine in its fuel intake conduit for supplying cooling liquids to the lower portion of the jacket of the engine from a portion of the system located entirely below said jacket, and for automatically maintaining the liquids in the jacket at a substantially predetermined level.

4. In a liquid cooling system for internal combustion engines having a jacket, the combination with a supply reservoir included in the system, of suction actuated means including a tank connected with the suction side of the engine, and conduits connecting the tank with the reservoir and jacket, respectively, in a manner to deliver liquids from the reservoir to the jacket through said tank under the influence of the engine suction thereon, and thereby maintaining a substantially predetermined level in the jacket.

5. In a liquid cooling system for internal combustion engines having a jacket, the combination with a supply reservoir included in the system, of a tank connected with the suction side of the engine, conduits connecting the tank with the reservoir and jacket, respectively, in a manner to deliver liquids from the reservoir to the jacket through the tank under the influence of the engine suction thereon and thereby maintaining a substantially predetermined level in the jacket, and valve means in the tank for controlling the action of the suction thereon in response to the rise and fall of the liquid level in the jacket.

6. In a liquid cooling system for internal combustion engines having a jacket, the combination with a supply reservoir included in the system, of a tank having vent and suction ports, the latter being connected with the suction side of the engine, conduits connecting the tank with the reservoir and jacket, respectively, in a manner to deliver liquids from the reservoir to the jacket through the tank under the influence of the engine suction thereon and thereby maintaining a substantially predetermined level in the jacket, and valve means associated with the tank and having a quick snap action for intermittently opening and closing said ports, in response to the rise and fall of the liquid level in the jacket.

7. The combination in a vapor cooling system for an internal combustion engine having a jacket, of a condenser connected with the steam space of the jacket, and a supply reservoir through which all of the

- cooling liquids of the system circulate and located lower than the jacket and connected with the liquid inlet thereof and with the lower portion of the condenser, respectively, ¹⁵ said reservoir having a capacity to hold a relatively large body of liquid to aid in reducing the heat of the condensate entering the liquid body from the condenser and thereby permitting liquids to be drawn to a ²⁰ higher point by suction.
8. The combination with the water jacket of an internal combustion engine of the suction and compression type, of a reservoir for the cooling liquids and through which all of the cooling liquids circulate, a discharge conduit leading from said reservoir to the jacket, a conduit for supplying liquids to said reservoir from a source at a lower level; and means for feeding the liquids through said supply conduit by the suction of the suction producing means of the engine.
- In testimony whereof I affix my signature this 27th day of December, 1926.

LESTER P. BARLOW.

cooling liquids of the system circulate and for the cooling liquids and through which all of the cooling liquids circulate, a discharge conduit leading from said reservoir to the jacket, a conduit for supplying liquids to said reservoir from a source at a lower level; and means for feeding the liquids through said supply conduit by the suction of the suction producing means of the engine.

10 higher point by suction.

8. The combination with the water jacket of an internal combustion engine of the suction and compression type, of a reservoir

In testimony whereof I affix my signature this 27th day of December, 1926.
